UNITED STATES PATENT OFFICE

MYRON H. RICHARDSON, OF CHICAGO, AND ALBERT E. GEBERT, OF WILMETTE, ILLINOIS, ASSIGNORS TO ADVANCE MACHINE COMPANY, OF CHICAGO, ILLINOIS, A CORPORATION OF ILLINOIS

VENDING MACHINE

Application filed February 4, 1927. Serial No. 165,783.

This invention relates to improvements in vending machines of the check controlled type, and one of the objects of the same is to provide an improved machine of this character embodying a plurality of containers mounted for rotation about a common axis, and improved means for controlling the rotation of the containers whereby they may be selectively positioned with respect to the delivery outlet of the machine and also with respect to an ejector which is common to the containers so that a selected article will be delivered when the check controlled mechanism is operated to actuate the ejector.

15 A further object is to provide in an improved machine of this character an improved ejector which is adapted to move in one horizontal plane while ejecting the article and during the movement of the ejector in one direction, and then drop down or out of the way so as to move in a different horizontal plane on the return movement, so that the articles in the containers will pass over the ejector when the containers are being shifted or rotated.

20 A further object is to provide an improved machine of this character in which the weight of the article will be supported by the containers so that when the containers are shifted or rotated the articles will not drag over a table or support, thereby avoiding frictional resistance to the movement of the containers.

25 A further object is to provide improved means controlled by the articles in the machine for controlling the operation of the ejecting mechanism.

To the attainment of these ends and the accomplishment of other new and useful objects as will appear, the invention consists in the features of novelty in substantially the construction, combination and arrangement of the several parts hereinafter more fully described and claimed and shown in the accompanying drawings illustrating this invention, and in which

30 Figure 1 is a side elevation partly broken away of an improved machine of this character constructed in accordance with the principles of this invention and with parts omitted.

Figure 2 is a right hand elevation of Figure 1.

Figure 3 is a detail perspective view of the lower portion of one of the containers showing a weight therein.

Figure 4 is a horizontal sectional view taken on line 4—4, Figure 6.

Figure 5 is a horizontal sectional view taken on line 5—5, Figure 6.

Figure 6 is a detail vertical sectional view taken on line 6—6, Figure 4.

Figure 7 is an enlarged detail vertical sectional view of one of the containers and showing the ejector and the operating mechanism therefor.

Figure 8 is a detail horizontal sectional view taken on line 8—8, Figure 6.

Figure 9, 10 and 11 are detail views partly in elevation, partly in section and partly broken away of the check controlled mechanism.

Figure 12 is an enlarged detail vertical sectional view taken on line 12—12, Figure 6.

Figures 13, 14, 15 and 16 are detail views partly in vertical section and partly in elevation, diagrammatically illustrating the different steps in the operation of the ejector.

Figure 17 is a detail view partly in elevation, partly in section and with parts omitted, showing a modified form of the invention.

Figure 18 is a sectional view on line 18—18, Figure 17, with parts omitted.

Figure 19 is a rear elevation of the cam for operating the ejector.

Referring more particularly to the drawings the numeral 20 designates the base of the machine having a top 21 which is provided with an opening 22 therein, the top being spaced for a considerable distance above the base and being maintained in position by means of suitable uprights 23.

A partition 24 is arranged within the bottom of the machine and spaced above the base 20, and this partition is provided with an opening 25 therethrough and through which the articles to be vended are delivered to be received by a chute 26 and conveyed to an outlet opening 27.

An upright shaft 28 is journaled in a suitable bearing in the base 20 and also in the

partition 24 and extends through and for any desired distance above the partition 24.

Secured to the shaft 28 in any suitable manner and arranged about the shaft are a plurality of containers 29, the bottoms of the containers being preferably formed by spaced supports 30, the latter being in turn supported above the partition 24 so that the entire weight of the articles 31 within the container will be supported out of contact with the partition 24, thereby obviating the creating of any resistance to the rotation of the containers by the dragging of the articles over the partition 24.

15 A collar 29^a may be provided to encompass the shaft 28 against the end of which a support 29^b carried between the containers is adapted to rest so as to assist in supporting the containers.

20 This collar 29^a together with another collar 29^c, if desired, are adapted to be interchanged with other collars, should it be desired or necessary to elevate or lower the containers with respect to the partition 24.

25 Secured also to the shaft 28 for rotation therewith and preferably adjacent the base 20, is a member 32 which is preferably angular in cross section so as to provide the faces 33. The member 32 is so shaped that there will be provided one face 33 for each of the containers 29 and co-operating with the faces 33 is a member 34 which is pivotally mounted as at 35, preferably upon the base 20 of the machine. A spring 36 is connected by one 30 end to the member 34 and is anchored as at 37, preferably to the base 20 and the normal tendency of the spring 36 is to move the member 34 against the edge or periphery of the member 32 so that as the member 32 is rotated with the shaft 28, the member 34 will contact with one of the faces 33 and thereby arrest the rotation of the containers 29 so as to cause them to assume positions over the delivery chute 26.

40 45 Any suitable means may be provided for rotating the containers, but a simple and efficient means embodies a shaft 38 which is journaled at one end in a bearing 39 and at the forward end preferably in the front wall 50 of the base, a handle 41 being provided on the shaft 38 so that the latter may be rotated.

50 Loosely mounted upon the shaft is a gear wheel 42 of any desired type. This gear 42 is arranged between a collar 43 which is secured to the shaft for rotation therewith and a collar 44 which is loosely mounted upon the shaft. Secured also to the shaft 38 for rotation therewith is another collar 45, and 55 interposed between these collars 44 and 45 is a spring 46, which tends normally to move the collar 44 against the gear 42 and cooperates with the collar 43 for yieldingly clamping the gear 42 to the shaft 38.

60 65 The collars 43 and 44 co-operating with

the gear 42 form a clutch which will permit the shaft 38 to rotate independently with respect to the gear 44 under abnormal conditions and thereby prevent damage to the machine.

70 Loosely mounted upon the shaft 28 is a gear wheel 47 which has connected with it for rotation therewith a ratchet wheel 48. These gears 47 and 48 may be supported by means of a collar or bearing 49 and co-operating with the ratchet wheel 48 is a pawl 50 which is pivotally mounted as at 51 upon the member 32. A spring 52 tends normally to hold the pawl 50 in contact with the ratchet wheel 48.

75 80 A gear 53 rotatable on an axis transverse to the axis of the shaft 28 meshes with the gear 47, and the gear 53 is secured to a shaft 54 journaled in suitable bearings 55.

85 Connected also with the shaft 54 for rotation therewith is a gear 56, with which the gear 42 meshes.

90 It will therefore be seen that when the handle 41 on the shaft 38 is rotated the gear 42 will be rotated under normal conditions as it will be frictionally clamped to the shaft 38. The gear 42 will rotate the gear 56, shaft 54 and gear 53, and through the medium of the gear 47 the ratchet wheel 48 will be rotated. The pawl 50 being secured to the member 32 will cause the member 32 and shaft 28 to be rotated when the member 32 is moving in the direction indicated by the arrow in Figure 5.

95 100 As the member 32 is rotated the member 34 will yield and if desired anti-friction rollers 57 may be provided on the member 32 intermediate the faces 33 so as to facilitate the rotation of the shaft 28 by the handle 41.

105 Secured to the lower face of the partition 24 and on opposite sides of the inlet opening of the chute 26, are guides 58 (see particularly Figure 12) and these guides are adapted to receive projections 59 which are carried by a member 60, and to which member 60 is connected an ejector 61. The member 60 is pivotally connected as at 62 with another member 63, which is in turn preferably pivotally supported adjacent one end thereof. The member 63 is adapted to be moved about its pivot by means of a suitable cam shaped device 64, which is adapted to be rotated in a manner to be hereinafter described, and during its rotation the cam shaped portion will successively engage lugs or projections 65-66 carried by the member 63.

110 115 Carried by the member 60 is an arm or projection 67 and a spring 68 is secured by one end to the projection 67 and by its other end to the member 63. This spring 68 tends normally to swing the member 60 about its pivot 62. That is to say when the member 60 and ejector 61 assume predetermined positions in the operation of the member 63 about its pivot the spring 68 will move to one side of the

pivot 62 (see Figure 13) to elevate the ejector 61 and position the projections 59 in alignment with the guides 58, so that upon the forward movement of the ejector the projections 59 will ride in the guides.

When, however, the ejector 61 and member 60 have reached a predetermined position in their cycle of operation, or the point at which the projections 59 will pass out of the guides 58 (see particularly Figure 15), the spring 68 will pass to the other side of the pivot 62 and will cause the ejector 61 and member 60 to drop about its pivot 62 so that during the return movement of the ejector it will move in a different and lower plane than the plane of its movement in the opposite direction, so as to permit the articles in the container to pass over the ejector.

When the cam 64 is rotated, and assuming the parts to be in the position shown in Figure 6, which is the same position as indicated in Figure 13, the high portion of the cam will engage the projection 65 on the member 63 and will swing the member 63 about its pivot in one direction to move the ejector 61 forwardly. During this cycle of operation the projections 59 will travel in the guideways 58 so as to eject one of the articles 31 from the container 29, as shown in Figure 14.

The member 63 and the ejector 61 will continue to travel in this direction of movement until the article is ejected from the container and until the projections 59, which are connected with the ejector, pass out of the guideways 58. At this time the spring 68 will have passed over the pivot 62 to the position shown in Figure 15, and the stress of the spring 68 will then swing the member 60 about its pivot 62, causing the ejector 61 to drop.

When the high part of the cam 64 engages the projection 66 on the member 63 it will move the member 63 in the opposite direction to retract the ejector. As the ejector 61 is being thus retracted from the position shown in Figure 15, the spring 68 will begin to move across to the other side of the pivot 62 so that just at about the time projections 59 which are connected with the ejector 61 reach the forward end of the guides 58 the spring 68 will hold these projections against the bottom of the guide (see Figure 16). A still further movement of the ejector 61 in the same direction will cause the projections 59, through the medium of the spring 68, to be moved upwardly into the position shown in Figure 13 or into a position in which the projections 59 will be in alignment with the guides 58.

This operation will be completed each time the cam 64 is given a forward and back movement.

The guides 58 are of such a length as to insure the movement of the projections 59 in the guides 58 until after the article is ejected and

the ejector has almost reached the limit of its ejecting movement, that is until the ejector has completed its stroke before the ejector can rise or fall.

In the present form of the invention the cam device 64 is shown in such a position that the articles 31 will be ejected upon the forward stroke of the ejector.

Should it be desired to cause the articles to be ejected on the return movement of the ejector instead of the forward movement, the cam device 64 may be removed from its operating shaft and reversed so that the high portion of the cam will engage the projection 66 in advance of its engagement with the projection 65 on the member 63.

This may be accomplished by reason of the fact that the cam device 64 is provided with an angular opening 69 which receives an angular shaped stud 70 that is connected with a shaft 71, the latter being rotated by means of a suitable hand 72 arranged in a convenient position for the operator.

A cushioning device may be provided for the ejector, preferably in the form of a spring 67^a which is preferably secured to the front wall of the base and is adapted to be engaged by the projection 67 just before the ejector reaches the limit of its movement in one direction. This will prevent damage to the machine and furthermore will also assist in starting the ejector in its movement in the opposite direction.

The cam device 64 is adapted to be actuated by check controlled mechanism preferably of the type and construction as disclosed in the United States patent to Alfred D. Antoine, No. 1,452,721, issued April 24, 1923, and which check controlled mechanism embodies a check carrier 73 (reference being had more particularly to Figures 9 to 11 of the drawings), having a check seat 74 therein.

The check carrier is adapted to be actuated by means of the handle 71 and the carrier 73 is adapted to be rotated when the proper check is inserted in the mechanism, until the carrier has assumed the position shown in Figure 10, at which time and under normal conditions the check or token 75 is adapted to be delivered from the carrier upon a support 76.

When the check rests upon this support it engages the locking or retaining element 77 of the check controlled mechanism so that when the check carrier 73 is reversed in the direction of rotation, a portion of the wall of the check seat will engage the edge of the check 75 to force the check from the support 76 and against the element 77 to swing the latter about its pivot 78 against the stress of a spring 79, thereby moving the portion 80 of the element 77 into a position that it will be rendered inactive with respect to a ratchet disc 81 to release the latter and there-

by permit the further operation of the check carrier 73 and with it the cam 64.

This portion of the check controlled mechanism, aside from the cam 64, constitutes no part of the present invention, as it is fully disclosed in the patent heretofore referred to.

It sometimes happens that it is attempted to actuate the mechanism when the machine is empty and in that event the check deposited by the operator should not be retained in the machine at a loss to the operator.

In the present invention means are provided whereby the mechanism will be automatically locked against operation after the machine has become empty and this is preferably accomplished through the medium of the articles themselves.

This mechanism will cause the check to be returned to the operator in the event that the containers are empty.

This is accomplished by means of mechanism which will now be described. A lever 82 (see particularly Figure 4) is pivotally mounted intermediate its ends as at 83 to a suitable support 84, and the lever is provided with a portion 85 that is arranged adjacent the path of movement of the containers. Connected with the lever is a bar or rod 86 which is so shaped that the end 87 thereof (see also Figure 6) is adapted to be projected into the path of movement of the periphery of the check 75 in the check seat 74 of the carrier 73 (see also Figure 10).

A spring 88 is provided which tends normally to move the end 87 of the bar 86 into a position that it will hold the check 75 in the seat 74 and prevent the check from being delivered from the check carrier when the seat is inverted.

The bar or rod 86 will assume this position when the container is empty.

When, however, articles 31 are present in the container, the lever 82 will be rocked about its pivot from the position shown in Figure 4 to the position shown in Figure 8, to withdraw the end 87 of the bar from beneath the check 75, thereby permitting the latter to drop upon the support 76 so that when the carrier 73 is moved in the opposite direction the check will be delivered into the machine and the ejector will be operated, the check falling down the passageway 89 (see Figure 6).

The operation of the lever 82 is controlled by means of a pivotally mounted member 90 (see particularly Figure 1), which is supported by the wall of the container, preferably by one end 91 of the member engaging in a suitable opening 92 in the container wall so that the member 90 will hang for free swinging movement.

The normal position of the portion 85 of the lever 82 is within the path of movement of the member 90.

When the container is empty and when the containers are rotated by the handle 41,

it will be manifest that the member 90 will strike the portion 85 of the lever 82 (see Figure 4), but as there is no resistance to the member 90 it will swing backwardly into the container thereby passing the lever 82 without rocking the latter about its pivot.

When, however, there are articles 31 in the container (as shown in Figure 8), the articles will hold the member 90 projected beyond the front of the container, with the result that when the container is then rotated the member 90 will engage the portion 85 of the lever 82 to rock the latter about its pivot 83 and thereby withdraw the extremity 87 of the rod 86 from beneath the check 75, thereby permitting the latter to drop into the machine.

A weight 93 is provided for the containers and this weight rests upon the articles. The portion of the front edge of the weight 93 adjacent the member 90 is cut away as at 94 so as not to interfere with the free swinging movement of the member 90 when the container is empty of articles.

The weight is also preferably provided with projections 95 which extend through the front of the container and co-operate with the sides of the opening in the front of the container so as to insure the proper positioning of the weight 93 in the container.

It will therefore be manifest that the operation of the device will be automatically controlled by the articles in the container.

Each of the containers is of the same general construction and each is provided with a freely swinging controlling member 90.

In the form of the invention which has just been described the machine is adapted to vend flat or angular shaped packages and in order to adapt the machine for vending round packages and at the same time prevent the packages from rolling out of the containers, the supports 30 may be provided with depressions 96 in which the ends of the articles 97 rest (see Figure 17).

A spring controlled gate 98 may be provided as a closure for the opening through which the article 97 is ejected from the container 29. The stress of the spring which controls the gate 98 is such that under normal conditions it will hold the articles in the container, but will readily yield under pressure exerted by the ejector upon the lowermost article 97.

The lowermost edge of the gate 98 is preferably deflected or flanged inwardly as at 98^a so as to project over the adjacent edge of the support 30 and serves as a means for preventing the insertion of an implement into the container and beneath the gate 98.

In this form of the invention and as a means for providing a lock for the gate 98 to prevent its swinging about its pivot until the container is directly in position to have the article ejected therefrom by the ejector,

a locking means may be provided which may consist of a projection or formation 98^b carried by and extending from the rear of the gate 98. A locking member 98^c having a notch 98^d therein is also provided and is secured to any fixed portion of the machine so that the notch 98^d will be in a position that the projection 98^b will pass therethrough when the container is in a predetermined position and the gate 98 moved about its pivot by the ejection of the article. When the container is moving or when it is not in a proper position to have the article ejected therefrom, the unnotched portion of the member 98^c will prevent the gate 98 from swinging about its pivot and no article can then be ejected or extracted from the container until the projection 98^b is brought into alinement with the notch 98^d.

20 A cover 99 preferably in the form of a dome constructed of transparent material, is provided to cover the containers 29 and to form a housing in which the containers rotate. The lower edge of this cover 99 (see particularly Figure 6) is adapted to rest upon a seat or shouldered portion 100 of the top 21 of the base which encompasses the opening 22 in the top of the base.

The lower extremity of the cover 99 is shouldered as at 101 and a ring 102 encompasses the bottom of the cover 99 and cooperates with the top 21 for locking the cover in position. The ring 102 is provided with hook shaped portions 103 adapted to enter openings 104 in the top 21 of the base and then rotated so that the hook portions will pass under the top of the base.

An apertured projection 105 is provided on the ring 102 through which an apertured member 106 passes, and the opening in the member 106 is adapted to receive a lock for locking the cover against removal.

While the preferred forms of the invention have been herein shown and described, it is to be understood that various changes may be made in the details of construction and in the combination and arrangement of the several parts, within the scope of the claims, without departing from the spirit of this invention.

What is claimed as new is:—

1. A vending machine including a container for the articles, a reciprocable ejector for successively ejecting the articles, a lever to which the ejector is pivotally connected, means for reciprocating the ejector transversely of the supply of articles, and means carried with the ejector and movable to one side or the other of said pivot for causing the ejector to operate in one plane during its movement in one direction and in another plane during its movement in the opposite direction.

2. A vending machine including a container for the articles, a reciprocable ejector

for successively ejecting the articles, a lever for reciprocating the ejector transversely of the supply of articles and to which lever the ejector is pivotally connected, means embodying a guideway for causing the ejector to operate in one plane during its movement in one direction and in another plane during its movement in the opposite direction, and movable with the ejector and automatically at predetermined times in the cycle of operation of the ejector to one side or the other of said pivot to cause the ejector to shift from one to the other of the said planes.

3. A vending machine including a plurality of containers adapted to be moved into and out of position with respect to a delivery outlet, means for thus moving the containers, a reciprocating ejector common to the containers and operable transversely of the supply of articles, guideways, means connected with the ejector and movable in and through said guideways, means for reciprocating the ejector, and means carried with the ejector and operating automatically to position the second recited means in alinement with said guideways to enter therein and move therethrough when the ejector moves in one direction and for causing the ejector, when said means leaves the guideways, to shift to a position to move in another plane on the return movement of the ejector.

4. A vending machine including a container for the articles, a reciprocable ejector for successively ejecting the articles, means for reciprocating the ejector transversely of the said supply, means for causing the ejector to travel in one plane during its movement in one direction and to travel in a different plane during its movement in the opposite direction, the last recited means embodying means pivotally connecting the ejector with its operating means, and a spring device movable from one side to the other of the axis of the pivot of said ejector for shifting the ejector about its pivot.

5. A vending machine embodying a shiftable container, there being a delivery opening in the container, a resiliently yielding closure for the opening, a formation carried by said closure and projecting therebeyond, a co-operating member beneath which said formation moves to maintain the closure against an opening movement during the movement of the container and until the container assumes a predetermined position, said co-operating member being shaped to permit the said formation to pass thereabove and the said closure to swing under predetermined conditions, and means for ejecting an article through said delivery opening.

6. A vending machine embodying a shiftable container, there being a delivery opening in the container, a resiliently yielding closure for the opening, a formation carried by said closure and projecting therebeyond, a co-op-

erating member beneath which said formation moves to maintain the closure against an opening movement during the movement of the container and until the container assumes a predetermined position, said co-operating member being shaped to permit the said formation to pass thereabove and the said closure to swing under predetermined conditions, and an ejector for moving the article against the said closure to swing the latter about its pivot and for ejecting the article.

In testimony whereof we have signed our names to this specification on this 20th day of January, A. D. 1927.
